UNITED STATES PATENT OFFICE.

JOHN E. WALSH, OF NEW YORK, N. Y.

COMBINED FLOATING CRANE AND ELEVATOR.

SPECIFICATION forming part of Letters Patent No. 451,903, dated May 5, 1891.

Application filed December 10, 1890. Serial No. 374,196. (No model.)

To all whom it may concern:

Be it known that I, JOHN E. WALSH, a citizen of the United States, and a resident of New York, in the county of New York and State 5 of New York, have invented certain new and useful Improvements in Combined Floating Cranes and Elevators, of which the following is a specification.

My invention relates to machines by means 10 of which vessels are rapidly loaded and unloaded; and the improvement consists in the combination of two or more masts erected on board of a scow or vessel carrying two double cranes or slotted arms each on a vertically- 15 adjustable sliding socket, to which they are connected, preferably, by universal joints. These arms again support either traveling trucks or elevator-legs, as may be required.

The improvement also consists in a number 20 of slotted beams mounted below the arms and carrying sheets of canvas or similar material, which, when spread over the hatches, will protect the workmen and the merchandise handled on both the vessel and the dock. 25 from the weather while discharging or loading.

In the accompanying drawings, Figure 1 is an elevation of an apparatus embodying these improvements placed between the vessels to 30 be loaded and unloaded and in reach of a dock. Fig. 2 is a plan view of Fig. 1 with the curtain removed. Fig. 3 is a side elevation and section through the dock, showing the protecting - canvas when spread. Figs. 4, 5, 35 and 6 are perspective views of details of the sliding sockets and their connecting-links for a derrick as used for unloading goods. Fig. 7 shows a sliding socket for a derrick carrying elevator-legs.

Similar letters of reference designate corresponding parts in all the figures.

Upon a scow or vessel S are mounted near its middle on opposite sides two upright poles A and B, preferably square, each having two 45 grooves A' A' and B' B' extending from a point above the deck all the way up.

To the pole A is fitted the sleeve a, Figs. 1, 2, 3, and 4, and held in position thereon by means of an upright shaft m, having screw- 50 threads cut in its upper portion engaging with that cut in the opening a' in the sleeve a. The shaft m is revolved by means of a crank m³, horizontal shaft m², and gearing m', and permits the sleeve a to be raised or lowered

on the pole A to any desired position. Into 55 two holes a² a², passing vertically through sleeve a, one at each side, are fitted the shanks of forks a³. A peculiarly-shaped forging or casting a⁴, carrying the rollers r r', is fitted to one end of an arm D and secured to a fork 60 a³ by means of a pin p passing through both horizontally, thus allowing the arm D to be swung up by turning it around the pin p and at the same time to be swung sidewise, when it, together with fork a³, will turn in a hole 65 a², through which the shank of fork a³ passes, and is prevented from slipping back by means of a split pin p' or similar device.

The arms or booms D are extending horizontally from the pole A when in action, and 70 in this position are supported by brace rods or chains connecting with the two ends of a collar or cross-cap A², fitting around the vertical trunnion upon the upper part of the mast A. They are slotted throughout almost 75 their entire length and carry each upon rollers and guided in the slot a traveling truck or trolley R, with a guide-roller r², over which the hoisting-rope h passes before being dropped through an opening in the truck to 80 the vessel or dock, while in the opposite direction it passes back over the roller r to a windlass w, mounted upon a raised platform S' of the scow S. Another rope h, having been secured to the outer end of truck 85 R, passes under and half-way around a roller r³, mounted in a stirrup-shaped bearing upon the outer end of an arm D, and from there back over the roller r' to a windlass w', mounted upon the platform A' upon the scow 90 S. Thus by alternately handling the windlass w and w' the load on the hoisting-rope can 95 be carried along the entire length of an arm D and raised or lowered, as required.

To secure free passage to the ropes, stirrup- 95 bands s are fastened to each arm D to connect with the brace-rods leading to the top of the mast A. The arms D are preferably of sufficient length to reach over a vessel and part of a dock.

The beams C, to which the canvas tents C' are secured, are slotted to the entire length of the slot in an arm D, and their slots are of sufficient width to allow the passage and some play for the hoisting-rope h. A long sheet of 105 canvas is secured to the outer sides of each beam C, and the inner sides are connected by a shorter strip, so that when spread as shown

in Figs. 1 and 3, it will form a tent which will protect the workmen, the hatches, and the merchandise, yet forming no impediment for the handling of the latter.

5 The employment of two arms D, each capable of being swung while at work in a horizontal plane to one side of the mast A, will allow the goods to be handled with great dispatch, as both arms could be used in one hatch 10 of a vessel, or two hatches could be worked with one arm for each at the same time, as shown in Figs. 2 and 3 of the drawings. The work having been completed, the arms D can be swung up by means of hoisting-tackle to 15 an almost vertical position, (shown at D', Fig. 1,) and the vessel can proceed to some other place, as required.

The arms or booms E, secured on a sleeve b, vertically adjustable on the mast B, are arranged 20 to carry elevator-legs F F, and are preferably of unequal length to facilitate the unloading of two vessels lying alongside of each other at the same time. The sleeve b is adjusted vertically upon the mast B in the same manner as the sleeve a upon the mast A by means of an upright shaft n, gearing n', shaft n², and crank n³. The arms E E are secured to ears b', like common hinges, by passing a hollow pin o through the projecting ears, as shown 25 in Fig. 2, and are held at any desired angle by means of blocks and fall, as shown in Fig. 1, or swung up to an almost vertical position when the work is done and the vessel is to be moved from one place to another.

30 The elevator-pulleys are rotated by means of bevel-gearing o³ and shafts o² and o', the latter passing through the hollow pin o, which secures the arms E E to the sleeve b, and the upright shaft i, carrying the pulley i', and 35 provided with a lengthy key-seat i² and a bevel-gear i³ secured by brackets n⁴ to the mast B, and passes through a forked bracket b², secured on sleeve b, which carries along the bevel-gear i³, the key of which is sliding 40 in the groove i², cut in shaft i, and making connection wherever the sleeve b may be placed on mast B by means of the shaft i² and the bevel-gear o⁴.

The scow S is provided with a chamber S² 45 to receive the grain to be unloaded, and above this an elevator T is erected, the leg T' of which reaches to near the bottom of the chamber S².

A steam boiler and engine K furnishes the power for working the bucket-elevators in the 50 leg T' as well as those in the legs F F. Suitable chutes f lead from the nozzles of the elevator-legs F F into the chamber S² in the vessel S, and a chute t is directed from the 55 nozzle of the elevator-leg T' to any hatch to be loaded.

The operation is then as follows: The scow S, with all her beams and arm raised, is placed alongside of a vessel to be unloaded and loaded 60 which has previously been fastened alongside of a dock, and two other vessels being brought alongside herself and each other at the

outer or free side of the scow it now proceeds to lower the arms of both cranes and to adjust the sleeves a and b to their proper height, 70 at the same time adjusting the brace-rods on the arms D so as to retain the latter in an almost horizontal position. The beams C are now adjusted and the canvas C' is spread and the hoisting-rope dropped to wherever it 75 is needed, the arm D having previously been swung over the hatches to be worked. At the same time another gang of men will adjust the arms E E and drop the elevator-legs F F into the hatches of the respective vessels and 80 adjust the chutes f f and t, when the work can proceed, as described, on three hatches simultaneously, while workmen and merchandise are entirely protected from the weather.

By the use of this combined floating crane 85 and elevator a vessel can be prepared to receive the grain from the elevator readily, which will serve as ballast, while the other hatches are discharging, thus getting the vessel ready for sea with great dispatch and being a help to secure her safety.

I am well aware that slotted arms and trolleys secured to sliding frames have been used before, and therefore do not broadly claim 90 their use; but

What I claim, and desire to secure by Letters Patent, is—

1. The scow S, having a mast A, carrying two independent booms D, secured to an adjustable sleeve a by means of the forks a³ and 100 the hinges a⁴, the latter carrying the rollers r r', the trolleys R, carrying the pulleys r², the pulleys r³, ropes h h', hoisting-winches w w', the screw m, crank m³, shaft m², and gearing m¹, as and for the purposes herein 105 shown and described.

2. The scow S, having a mast B, carrying two independent booms E, secured to an adjustable sleeve b, two elevator-legs F of unequal length, the screw n, gear n', shaft n², 110 and crank n³, with the upright shaft i, carrying the pulley i', the gearing i³, o³, and o⁴, the shafts o', o², and i⁴, pulleys and belts, the elevator T, entering the chamber S², the chutes t and f, and the engine K, as and for the purposes herein shown and set forth.

3. A loading and unloading apparatus comprising the scow S, having a chamber S² and a mast A, carrying two independent booms D, secured to an adjustable sleeve a and provided with trolleys, pulleys, ropes, and winches, the mast B, carrying two independent elevator-legs F F, of unequal length, the booms E E, secured to an adjustable sleeve b, and engine K, pulleys, belts, shafts, and gear, the 120 elevator T, and the chutes f and t, as and for the purposes herein shown and described.

Signed at New York, in the county of New York and State of New York, this 9th day of December, A. D. 1890.

JOHN E. WALSH.
